US0D1055484S

(12) **United States Design Patent** (10) **Patent No.:** **US D1,055,484 S**
(45) **Date of Patent:** **** Dec. 31, 2024**

(54) **SOLE**

(71) Applicant: **Qiqi Shi**, Anqing (CN)

(72) Inventor: **Qiqi Shi**, Anqing (CN)

(**) Term: **15 Years**

(21) Appl. No.: **29/832,550**

(22) Filed: **Mar. 29, 2022**

Related U.S. Application Data

(63) Continuation-in-part of application No. 29/760,439, filed on Dec. 1, 2020, now abandoned.

(51) **LOC (14) Cl.** **02-04**

(52) **U.S. Cl.**

USPC **D2/947**; D21/763

CLAIM

The ornamental design for a sole as shown and described.

DESCRIPTION

FIG. 1 is a front perspective view of a sole showing my new design;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof; and,

FIG. 8 is a right-side view of a sole showing wheel in other position.

The broken lines in the drawings depict portions of the sole that form no part of the claimed design.

1 Claim, 8 Drawing Sheets
